UNITED STATES PATENT OFFICE.

HENRY ADALBERT SMITH, OF OMAHA, NEBRASKA.

WHIP-SOCKET.

SPECIFICATION forming part of Letters Patent No. 513,736, dated January 30, 1894.

Application filed March 27, 1893. Serial No. 467,893. (No model.)

To all whom it may concern:

Be it known that I, HENRY ADALBERT SMITH, of Omaha, in the county of Douglas and State of Nebraska, have invented certain new and 5 useful Improvements in Whip-Sockets; and I do hereby declare the following to be a full, clear, and exact description of the invention, such as will enable others skilled in the art to which it appertains to make and use the same.

10 My invention is an improved grip for whip-sockets or other containing receptacles, designed for greater security, cheapness and durability of construction and certainty of operation.

15 My invention more particularly resides in the novel combination, construction and arrangement of parts hereinafter fully specified in the accompanying drawings and pointed out in the claim.

20 Figure 1 is a perspective view of a whip-socket with parts broken away to show the interior, and Fig. 2 is a vertical section with whip inserted in the socket.

A is the main part of the socket, or what is 25 known as the case, (or a containing receptacle) and may be of ordinary exterior form.

Within the socket (or case) and secured thereto, preferably at points near the top of the same are strands of wire or other strong 30 and pliable material B, C, and D, E which extend downwardly and are secured at their lower ends B, C, and D, E to a revoluble base F, which base revolves independently from the main socket (or case) A, which is held stationary by a support G which should be attached to the dash board of the carriage or wagon. The wires or strands B, C, D, E, may be separate or continuous, when continuous B and C extending up (or down) and back 35 to end of starting, but its center securely held to the opposite part of the receptacle from where started, (same with D and E.)

The construction and arrangement of the several parts, when used as a whip-socket being thus made known, the operation and the 45 advantages of the same will it is thought be readily understood.

After the whip is inserted in the socket the revoluble base is turned either to the left or to the right by turning the whip and by so 50 doing the strands are wound around the whip-stock and thus securely holding the whip in the socket.

It will be understood that the strands are normally slack, and when the whip-stock or 55 other device to be secured thereby is inserted therein and turned, said strands tighten around the said stock.

The object of the invention is primarily to afford such a safeguard, that a whip, tool, implement, or other article, is not liable to be 60 stolen therefrom, by making it impossible to take them from the grip without first turning the revoluble base.

I do not confine my invention to any particular form of case inclosing the grip or of 65 the revoluble base, but

What I claim, and desire to secure by Letters Patent, is—

In a device of the character set forth, the 70 combination of a case, a revoluble base, and interiorly located strands secured to said base and the upper part of the case, substantially as described.

In testimony whereof I have signed this 75 specification in the presence of two subscribing witnesses.

HENRY ADALBERT SMITH.
